A. J. FUETTER,
FUEL OIL BURNER,
APPLICATION FILED JUNE 23, 1920.

1,417,819.

Patented May 30, 1922.

UNITED STATES PATENT OFFICE.

ALBERT J. FUETTER, OF CLEVELAND, OHIO.

FUEL-OIL BURNER.

1,417,819.

Specification of Letters Patent. Patented May 30, 1922.

Application filed June 23, 1920. Serial No. 390,993.

To all whom it may concern:

Be it known that I, ALBERT J. FUETTER, a citizen of the United States, residing at Cleveland, in the county of Cuyahoga and State of Ohio, have invented a certain new and useful Improvement in Fuel-Oil Burners, of which the following is a full, clear, and exact description, reference being had to the accompanying drawings.

10 This invention relates to fuel oil burners of the concentric jet type.

An object of my invention is the construction and arrangement of nozzles in the burner in such manner that the efficient atomization of the oil is effected by a whirling discharge of the atomizing agent. Another object is the arrangement of the parts to provide for rapid and accurate relative adjustment of the nozzles. Other features 20 and objects include a construction that is simple and capable of being cheaply manufactured, that may be readily assembled and taken apart, and that is durable in use.

In the drawings Fig. 1 is a side elevation 25 of a burner constructed according to my invention; Fig. 2 is a central vertical section therethrough; Fig. 3 is a side elevation of one of the nozzle members showing the oil passageway and the spiral flutes on its exterior for imparting a whirling movement 30 to the air discharge; Fig. 4 is a longitudinal section through the same; and Fig. 5 is an end view thereof.

Referring to the drawing by numerals, 10 35 designates a nozzle cap having a central bore 11, with a restricted discharge opening 12. The exterior surface 12 of the cap is threaded as at 14, and provided with an annular flange 15 intermediate the ends. A combustion hood 18 having an internal threaded flange 19 at its base is adapted to be threaded 40 over the discharge end of the cap 10 in abutting engagement with the flange 15. The other end of the cap 10 is adapted to 45 receive the threaded flange 20 of a member comprising a portion of an air conduit, the member shown comprising the hollow casting 21.

The member 21 may satisfactorily support a nozzle member complementary to the 50 cap 10, such member, called the needle point, comprising a portion of an oil conduit, and being designated by the numeral 22. As shown, the wall 24 of the member 21 opposite 5 the nozzle cap 10 is thickened and has an interiorly threaded opening 26 in alignment

with the bore 11 of the nozzle cap, and adapted to receive the exteriorly threaded portion 27 of the member 22. With such a connection the member 22 may be readily 60 adjusted longitudinally with respect to the member 10 by applying a wrench to a squared portion 28 and turning the member 22 in either direction, thus causing its end to move into or away from the nozzle cap 10. 65

The member 21, preferably comprising an enlarged portion of the air supply conduit, is connected with a valve 30 through pipes 31 and any suitable union 32. The member 22 has an oil tight, rotatable engagement 70 with an oil conduit, as shown comprising the threaded connection 33 with a casting 34, connected through pipes 36 and a union 38 with a valve 39.

The member 22 comprising a needle point 75 and portion of the oil conduit forming part of the nozzle has a bore 40, having a restricted discharge opening 42. The end portion of the member 22, adapted to be positioned within the bore 11 of the nozzle cap 80 10, is reduced as at 43 and provided with spaced, spirally fluted, enlarged portions 44. These flutes 44 cause air passing through the member 21 into the bore 11 to be whirled as it passes over the extreme tip 45 of the 85 member 22 into proximity with the stream of oil discharged from the orifice 42 of the member 22, and causes a very efficient atomization of oil in the passageway 12 of the nozzle cap 10. 90

The combustion hood 18 has a plurality of spaced openings 48 to permit the entrance of additional air sufficient to support the efficient combustion of the fuel within the hood. 95

The casting 21 is shown having a chamber within the hollow boss 50 with an opening therein closed by a threaded plug 52. By removal of this plug any impurities which may be in the member 21 may be easily 100 blown out. If desired, air from a source under different pressure may be supplied to the burner through such opening. The casting 34 comprising a portion of the oil conduit is shown having a drain cock 54. 105

In use, air and oil may be supplied to the burner above described through cocks such as 30 and 39, either or both under pressure as desired. The oil flows freely through the bore 40 of the member 22 to the reduced 110 opening 42 from whence it emerges as a fine jet with considerable velocity. The air passes

through the air conduit and into the bore 11 and around the exterior of the end 45 of the needle point, passing through the spiral grooves 44 which cause it to discharge into 5 the reduced bore 42, into proximity with the oil, in a rapidly whirling stream. The whirling discharge of the air under pressure atomizes the oil causing it to leave the nozzle in the form of a fine spray which may be 10 efficiently burned; an additional supply of air to properly carry on combustion being drawn in through the openings 48 by the injector action of the jet. Should the nozzle become clogged at any time, the drain cock 15 54 may be removed and a fine wire inserted through the member 22 to remove the obstruction.

Having thus described my invention, I claim:

- 20 1. In a fuel oil burner, a nozzle comprising two coaxial apertured members, means for supplying oil through one of the members and air through the other, a combustion hood on said nozzle and a conduit for supplying air to said nozzle, said nozzle and said combustion chamber being coaxially arranged, said oil supplying member having spiral vanes thereon.
- 25 2. In a fuel oil burner, a nozzle member comprising a body having an opening therethrough restricted at one end to form a discharge opening, said nozzle member having an annular flange intermediate its ends, a combustion hood secured upon one end of 35 the nozzle and an air conduit member se-

cured upon the other end of the nozzle, said conduit member having a pair of openings, an oil supply pipe extending through said conduit and adjustably mounted in one of said openings, said pipe having an aperture therethrough leading to a point adjacent said discharge opening and having two sets of spirally arranged vanes upon the periphery thereof and located within the opening in said nozzle, said second opening in the air conduit communicating with a source of air supply.

3. In a fuel oil burner, a nozzle member comprising a body having restricted discharge opening and an enlarged chamber, said nozzle member having external threads thereon and having an annular flange intermediate the two ends, a combustion hood threaded upon one end of the nozzle and an air conduit member threaded upon the other end of the nozzle, said conduit member having a pair of openings, an oil supply pipe adjustably mounted in one of said openings, said pipe having an aperture therein leading to a point adjacent said discharge opening and having spaced spirally arranged flanges upon the periphery thereon and located within said enlarged chamber, said second aperture in the air conduit communicating with the air supply and means on said oil feed pipe whereby the same may be adjusted to control the supply of air.

In testimony whereof, I hereunto affix my signature.

ALBERT J. FUETTER.
